UNITED STATES PATENT OFFICE

2,514,271

PRESS GUARD

Walter S. Wilkins, Wednesbury, England, assignor to Wilkins & Mitchell, Limited, Darlaston, England

Application July 17, 1946, Serial No. 684,104
In Great Britain July 21, 1945

6 Claims. (Cl. 192—134)

1

The invention relates to guards for power presses and has for its object to effect improvements therein.

Heretofore usually guards for presses have been operated by the moving head of the press; but according to the present invention they are opened and closed by hand, locking means being provided to ensure that the guard can only be opened when the head of the press is fully up; and the press cannot be started with the guard open.

While the invention is applicable to a press having only a front guard, it is more especially applicable to a press in which there are two operators (and two guards), one at the front of the machine and one at the rear. In the latter case locking means are provided which prevent the opening of the rear guard until the front guard is opened and the closing of the front guard until the rear guard is closed.

According to an important feature of the invention each guard is divided longitudinally into an upper and lower part each guided for vertical movement, the arrangement being such that, when the top part is moved up, the lower part moves down.

A convenient embodiment of the invention, as applied to a press having a front and a rear guard, is described with reference to the accompanying drawings; in which:

Figure 1 is a front elevation, partly broken away, of the press, showing the front guard in the closed position and showing a vertically moving head in its upmost position.

Figure 2 is a view partly broken away, of the right hand end of the press, also showing the head in its upmost position and showing both guards closed.

Figure 3 is a view partly broken away, of the left hand end of the press showing the moving head raised, and both guards closed.

Figure 4 is a view, corresponding to Figure 3, but showing both guards open.

Figure 5 is a view in somewhat diagrammatic form illustrating a modification.

In these drawings, the number 7 indicates the moving head of the press and 8 indicates the usual fixed table or bolster. 10 indicates the main frame of the machine having at its two sides two front guides 11, 11, in which slide upper and lower

2

guard frames 12, 13. 14 is a shaft passing across the front of the upper part of the press and being journalled in bearings 15, 15, secured to upward extensions of the guides 11, 11. The shaft 14 has rigidly mounted thereon two sprocket wheels 16, 16, with the teeth of which engage endless chains 17, 17, which also pass round sprocket wheels 18, 18, rigidly mounted on a shaft 19 journalled in bearings 20, 20, secured to downward extensions of the guides 11, 11. The lower guard 13 is anchored at its two sides to the front portions of these chains by brackets 21, 21, and the upper guard 12 is anchored to the rear portions of these chains by brackets 22, 22. The guard frames are opened and closed by hand; and, owing to their being coupled by the chains, the raising of the one causes the lowering of the other.

This method of coupling the two frame parts together has the advantage that the one frame balances the weight of the other. The forming of the guard in two parts has the advantage that each of the frame parts needs to be moved on half the distance which would be required for a single piece guard.

The shaft 14 carries at its right hand end a disc 23 having a radial slot 24, see Figure 2. When the frames 12 and 13 are closed the disc 23 will have been turned by the shaft 14 to such position that the slot is directed vertically upward (see Figure 2).

The clutch which causes the engagement of the gear which raises and lowers the moving head is operated by an air valve 25 coupled to a vertical rod 26 joined at its lower end to a hand lever 27. The rod 26 carries a plate 28, which when the rod is moved down can enter the said slot 24, when the latter is extending vertically upward as it is when the frames 12 and 13 are closed. Thus the press can be started when the frames 12 and 13 are closed. When, however, the frames 12 and 13 are open the slot 24 is not opposite the plate 28, so that the latter cannot enter the slot and can only ride on the periphery of the disc 23. Thus the rod cannot be depressed to start the machine except when the frames 12 and 13 are closed.

47 is a trip lever having a downward arm 44 carrying a roller 45 which is engaged by an abutment 46 on the moving head, so placed that the lever 47 is rocked to stop the press each

time the moving head is nearing its upmost position.

There is another attendant at the rear of the machine the opening to which is guarded by two frames 29, 30, which are identical with and are guided similarly as the frames 12 and 13. They are controlled by endless chains 31, 31, which pass over upper sprocket wheels 32, 32, rigidly mounted on a shaft 33 which passes across the upper part of the rear face of the press. This shaft is similar to the shaft 14; but it does not carry a disc corresponding to the disc 23.

The shaft 14 has fixed on its left hand end a disc 34 having a V-notch 35 and the shaft 33 carries at its corresponding end a similar disc 36 having a V-notch 37. Placed transversely across the left hand end of the press is a rod 38 guided for endwise movement and the rod has its two ends 39, 40, of V-shape to adapt them to enter the V-notches 35 and 37 in the discs 34 and 36.

When the front frames 12 and 13 are closed the V-end 39 is riding on the periphery of the disc 34 and the other end 40 of the rod is engaging in the notch 37 of the disc 36 (see Figure 3) thus preventing the opening of the rear guard. When, however, the front guard is fully open, the notch 35 comes opposite the V-end 39 of the rod 38 so that the rear guard can be opened, because the disc 36 can then turn forcing the V-end 40 out of the notch 37 and consequently causing the V-end 39 to enter the notch 35 thus to lock the front guard in its open position. Hence it follows that the rear guard can only be opened when the front guard is open and the rear guard must be closed again before the front guard can be closed.

As will be understood it is not essential to carry the chains 17, 31 round lower sprockets as they may terminate at the respective frames; but endless chains are greatly preferred.

It will also be understood that two armed levers with depending chains or rods may be substituted for the upper sprockets. Such a lever 41 is shown in Figure 5, mounted on the shaft 14, there being pivoted to the ends of the lever two rods 42, 43, pivotally connected at their lower ends to the guard frames 12 and 13.

It will also be understood that each guard may comprise only a single frame, in which case a balance weight would take the place of the other frame.

Having fully described my invention, what I claim and desire to secure by Letters Patent is:

1. A power press comprising a front guard guided for vertical movement, a shaft disposed above said guard and parallel to the front of the press, two parts rigidly secured on said shaft, suspension means connecting said parts to the two ends of said guard said parts being of such form that they are turned to turn said shaft when said guard is raised and lowered, a disc on one end of said shaft, a radial slot in said disc, a hand-operated part moved to start the operation of the press, and a plate carried by said hand-operated part and adapted to enter said slot when said hand-operated part is operated to start the said operation; but only when said guard is closed, the plate riding on the periphery of the disc to prevent such operation when the guard is open.

2. A power press comprising a front guard guided for vertical movement, a shaft disposed above said guard and parallel to the front of the press, two chain wheels rigidly secured on said shaft, two chains passing over and engaging with said chain wheels and connecting with the two

ends of said guard, a disc on one end of said shaft, a radial slot in said disc, a hand-operated part moved to start the operation of the press and a plate carried by said hand-operated part and adapted to enter said slot when said hand-operated part is operated to start the said operation, but only when said guard frames are closed, the plate riding on the periphery of the disc to prevent such operation when the guard is open.

3. A power press comprising a guard formed in two parts, an upper guard frame and a lower guard frame, one of which is raised and the other lowered to open the guard, vertical guides in which said guard frames are guided, a shaft disposed above said frames and parallel to the front of the press, two chain wheels rigidly secured on said shaft, two chains passing over and engaging with said chain wheels and each chain connecting with the corresponding ends of the said guard frames, a disc on one end of said shaft, a radial slot in said disc, a hand-operated part moved to start the operation of the press and a plate carried by said hand-operated part and adapted to enter said slot when said hand-operated part is operated to start the said operation; but only when said guard frames are closed, the plate riding on the periphery of the disc to prevent such operation when the guard is open.

4. A power press adapted for attendance by two operators, one at the front and one at the rear of the press, press guards at the front and rear of the press, two shafts positioned over said guards, and turned by the raising and lowering of said guards, a disc on each of the two said shafts and both positioned at the same end of the press, a V-notch in each disc, a bar passing across said end of the press, and guided for endwise movement, V-shaped ends to said bar adapted to enter said notches, and said notches so positioned in said discs that, when the notch in the disc at the front of the press is opposite the respective V-shaped end of the bar, the rear end of the bar can be forced out of the respective notch by the turning of the respective disc, the front end of the bar entering the notch in the front disc, whereby the rear guard can be opened and the front guard is locked in the open position and cannot be closed until the rear guard is closed.

5. A power press adapted for attendance by two operators, one at the front and one at the rear of the rear of the press, press guards at the front and the rear of the press and means whereby the rear guard can only be opened when the front guard is open, and whereby the front guard is locked in the open position by the opening of the rear guard and can only be closed when the rear guard is closed, and means whereby the front guard is locked in the closed position when the press is operated.

6. A power press comprising a front guard guided for vertical movement, a shaft disposed above said guard parallel to the front of the press, two parts secured on said shaft, suspension means connecting said parts to the two ends of said guard, said parts being of such form that they turn said shaft when said guard is raised and lowered, a similar guard at the rear of the press, a rear shaft passing over said guard, a disk on each of said shafts positioned at the same end of the press, a V-notch in each of said disks, a bar passing over the end of the press, the same being guided for endwise movement, V-shaped ends to said bar adapted to enter said notches, said notches being so positioned that when the

notch in the disk at the front end of the press is opposite the respective V-shape bar, so that the bar may be forced out of the respective notch by the turning of the respective disk, the front end of the bar entering the notch in the front disk, whereby the rear guard can be opened and the front guard is locked in the open position and can not be closed until the rear guard is closed.
